UNITED STATES PATENT OFFICE

116,839

DESIGN FOR A CHAIN

Frederick A. Dieterich, Maplewood, N. J., assignor
to Universal Chain Co. Inc., a corporation of
New Jersey

Application March 8, 1939, Serial No. 83,434

Term of patent 14 years

To all whom it may concern:

Be it known that I, Frederick A. Dieterich, a citizen of the United States, residing at Maplewood, in the county of Essex and State of New Jersey, have invented a new, original, and ornamental Design for a Chain, of which the following is a specification, reference being had to the accompanying drawing, forming a part thereof.

Figure 1 is a plan view of a chain showing my new design.

Figure 2 is an edge view,

Figure 3 is a plan view opposite to that shown in Figure 1, and,

Figure 4 is an end elevational view of one of the links shown in full lines.

The essential feature of the design resides in the links shown in full lines.

I claim:

The ornamental design for a chain, as shown and described.

FREDERICK A. DIETERICH.
